BEADING

William C. Ferguson, St. Louis, Mo., assignor to
The Pressite Engineering Company, St. Louis,
Mo., a corporation of Missouri

Application October 14, 1944, Serial No. 558,636

1 Claim. (Cl. 280—153.5)

1

This invention relates to car body joints, and with regard to certain more specific features to automotive and like body and fender joints including beading for packing and trimming.

Among the several objects of the invention may be noted the provision of improved means between fenders or the like and adjacent body parts which will waterproof and trim the joint; the provision of beading of the class described which will provide exterior trim adapted substantially to retain its proper color throughout the life of an automobile without substantial deterioration due to mechanical wear and tear or weathering; the provision of beading of the class described which will freely adapt itself to fender and body curves without undue buckling; and the provision of beading of the class described which may be applied more easily and economically with a consequent reduction in cost. Other objects will be in part obvious and in part pointed out hereinafter.

The invention accordingly comprises the elements and combinations of elements, features of construction, arrangements of parts, proportions thereof, and features of composition, which will be exemplified in the structures and products hereinafter described, and the scope of the application of which will be indicated in the following claim.

In the accompanying drawing, in which are illustrated several of various possible embodiments of the invention,

Fig. 1 is a diagrammatic vertical section through a rear fender of an automobile showing one form of the invention;

Fig. 2 is an enlarged perspective view of a segment of the bead shown in Fig. 1;

Fig. 3 is a fragmentary view similar to Fig. 2 but showing an optional form of said bead;

Fig. 4 is a vertical section similar to the section of Fig. 1, except that it is enlarged and shows the optional packing element;

Fig. 5 is a vertical section taken on line 5—5 of Fig. 4;

Fig. 6 is a perspective view showing a step in the production of said packing element of Fig. 4; and,

Fig. 7 is a perspective view showing another step in the production of said last-named element.

Similar reference characters indicate corresponding parts throughout the several views of the drawings.

Automobile fenders and other body parts on various vehicles and the like are provided in

2

their joints with beading which is for the purpose of rattle-proofing, moisture protection and trim. Heretofore this beading has been made up of a webbed portion, for example, having been composed of multi-ply paper, fabric and asphalt. This was made up as a strip with suitable notches cut from one edge for accommodating fender bolts and the like. On the other edges was formed a bulbous selvage by bending fabric or the like over the edge of the web and sewing. In order to maintain the fabric loop in a bulged condition, it was formed over a stringer. The exterior of the resulting bulbous selvage beading was generally finished in imitation of the finish of the car. A disadvantage of this product was that the multi-ply fabric strip could not readily be bent to follow the contours of fenders and the like without serious crimping and deterioriously affecting the appearance of the trim. In addition, being exposed outside of the car, it was subject to abrasion, accidents and the like which often removed its superficial finish, and even sometimes broke it. In either event, invisible repairs could not be made. In addition, the trim frayed and did not weather well. By means of the present invention these disadvantages are avoided and in addition the fender or like joint is much better waterproofed.

Referring now more particularly to Fig. 1, there is shown at numeral 1 a fragmentary portion of an automobile body having a section 3 to which a fender 5 is attached. As fenders are made they carry an inner flange 7. Bolts 9 are used for holding this flange to a channel strip 11, or, sometimes the bolts will hold to the adjacent body without the use of the channel strip.

The beading strip to be used is such as shown in Fig. 2. This is constituted by a web portion 13 formed integrally with a round edge bead 15. This is composed preferably of an extruded flexible, plastic resin such as is, for example, known to the trade as "Saran." Materials of this type include the Vinylites, polystyrene, ethyl cellulose, cellulose acetate, cellulose acetate butyrate and others with suitable fillers. They may readily be extruded, thus making their construction economical. These materials may also readily be impregnated throughout with suitable coloring pigments to match the body finish. Thus later abrasions, wearing and rubbing as during polishing of a car will not obliterate the color. The dots 12 indicate this dispersed coloring matter. In addition, these materials are flexible, thus making it much easier to shape the beading

to the various curvatures required. They are also tough and weather-resistant.

An exemplary notch 17 for accommodating a holding bolt 9 is shown in Fig. 2. Others are spaced at suitable intervals.

In Fig. 3 the web 13 is formed integrally with a tubular edge bead or fillet 19, instead of the solid one of Fig. 2. This semi-tubular construction has an additional advantage of increased flexibility of what may be generically called the 10 bulbous fillet portion of the beading.

Figs 4 and 5 show at the top application to an automobile fender of the Fig. 3 form of the invention. Figs. 4 and 5 in addition show another element of the invention which has for its purpose the complete prevention of moisture entry by protection on the lower edge of the flange 1. This is accomplished by grooving the flange as indicated at 21 and inserting a composite strip member such as illustrated in Figs. 6 and 7. This member has two parts and in Fig. 6 is shown a preliminary step in assembling these parts. One part is constituted by an initially flat extruded strip 23 composed of say 25% by weight of a polymerized saturated hydrocarbon resin of high molecular weight such as what is known to the trade as "Vistanex." This is a poly-iso-butylene compound. It has physical properties intermediate between rubber and the non-elastic plastics. This substance is mixed with 75% by weight of a highly blown asphalt, such as No. 3 "Korite." The percentage ratio of "Vistanex" to asphalt may vary over wide limits, depending upon the degree of tackiness desired of the ultimate product.

A flat strip of the stated "Vistanex"-asphalt product is laid out as illustrated in Fig. 6 and a soft packing strand or filler 25 is laid on it. This filler should be soft or loose to give bulk to the bulbous portion in which it will ultimately appear.

As indicated in Fig. 7, the tacky strip 23 is turned up to envelop the filler 25 and the opposite edges are stuck together as indicated. The inherent tackiness of the "Vistanex"-asphalt compound causes the material to retain the shape shown in Fig. 7 and to retain exterior tackiness also for application to adjacent surfaces.

Application of the waterproofing strip of Fig. 7 is quite easy. It is readily attached to one or the other of the parts to be joined and these may then be brought together and fastened. The bolts 9 are then drawn up, and the resulting squeezing action assures a well-packed waterproof inside joint.

An advantage of the invention is that the tacky strip of Fig. 7 is particularly adapted for application to inside joints such as associated with the groove 21. These are difficult to reach for insertion of packing even after only partial assembly. The packing of Fig. 7 may be tacked either to the body 3 or the fender flange before these are brought together. In the case of the packing of Figs. 2 and 3, tackiness is not desired because it is desirable to insert the strip after a partial as-

sembly of the fender with the body, which involves slipping the web 13 into position and tucking the bulbous margin into filleting position by means of the thumb or some working tool.

It is also to be noted that the one-piece or integral characteristic of the flange 13 and bulbous edge 12 (Fig. 2), or the flange 13 and the bulbous edge 19 (Fig. 3), facilitates edgewise sliding application of the packing strip without the buckling that was heretofore encountered where the strip was constituted by an assembly.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

A car body joint comprising a first body member, a second body member having a flange secured to said first body member with a pair of flexible packing strips engaged therebetween, said flange having a longitudinal groove therein adjacent a margin facing said first body member, each packing strip comprising a web having a bead only on one longitudinal edge thereof, one of said strips having its web engaged between the first body member and the inner portion of said flange with its bead disposed in the corner at the juncture of said body members, the other strip having its bead disposed in said groove and its web engaged between said first body member and the portion of said flange between the groove and the outer margin of the flange, said other packing strip being tacky.

WILLIAM C. FERGUSON.
